(57) **CLAIM**

The ornamental design for a portion of a computer display with a computer icon graphic, as shown and described.

DESCRIPTION

FIG. 1 is a front view of a portion of a computer display with a computer icon graphic of the present invention; and, FIG. 2 is a front view of a second embodiment thereof. The broken line drawing of a portion of a computer display with a computer icon graphic is for illustrative purposes only and forms no part of the claimed design.
